(57) **CLAIM**

The ornamental design for connection for radio frequency identification device, as shown and described.

DESCRIPTION

FIG. 1 is a perspective view of a connector for a radio frequency identification device according to the principles of the present invention;

FIG. 2 is a top view of the connector shown in FIG. 1;

FIG. 3 is a bottom view of the connector shown in FIG. 1;

FIG. 4 is a side view of the connector shown in FIG. 1;

FIG. 5 is a side view of the connector shown in FIG. 1 180 degrees from the side view shown in FIG. 4;

FIG. 6 is a side view of the connector shown in FIG. 1 90 degrees from the side view shown in FIG. 4; and,

FIG. 7 is a side view of the connector shown in FIG. 1 180 degrees from the side view shown in FIG. 4.
